(57) **CLAIM**

The ornamental design for a guitar body, as shown and described therein.

DESCRIPTION

FIG. 1 is a front elevational view of a guitar body showing my novel design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof; and,

FIG. 7 is a perspective view of a guitar body of the present invention.

The details shown in broken lines in FIGS. 1, 2 and 7 are for illustrative purposes only and form no part of the claimed design.
